(57) CLAIM

The ornamental design for a chair leg cover, as shown and described.

DESCRIPTION

FIG. 1 is a front, right and top perspective view of a chair leg cover showing my new design;

FIG. 2 is a rear, left and bottom perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The broken lines in the drawings depict portion of the chair leg cover that form no part of the claimed design. The unshaded surfaces shown between solid and broken lines in FIG. 7 forms no part of the claimed design.
